235,646

HEATER, CIRCULATOR, AND TEMPERATURE CONTROL FOR A FLUID-TYPE HEATING PAD

Bhaskar Kumar Agarwala, West Los Angeles, Calif.,
assignor to Everest & Jennings, Inc., Los Angeles, Calif.

Filed Aug. 24, 1973, Ser. No. 391,061

Term of patent 14 years

Int. Cl. D23—03

U.S. Cl. D23—77

FIG. 1.

FIG. 2.

FIG. 1 is a perspective view of a heater, circulator, and temperature control for a fluid-type heating pad illustrating the top and side.

FIG. 2 is a perspective view illustrating the bottom and opposite side.

I claim:

The ornamental design for a heater, circulator, and temperature control for a fluid-type heating pad, as shown and described.
